UNITED STATES PATENT OFFICE.

JULIUS HENRIK WEST, OF BERLIN, GERMANY.

AUTOMATIC APPARATUS FOR TELEPHONE-SWITCHBOARDS.

SPECIFICATION forming part of Letters Patent No. 605,659, dated June 14, 1898.

Application filed July 8, 1896. Serial No. 598,446. (No model.)

To all whom it may concern:

Be it known that I, JULIUS HENRIK WEST, a subject of the King of Denmark, residing at Berlin, in the German Empire, have invented 5 certain new and useful Improvements in Automatic Apparatus for the Working of Telephone-Stations; and I do hereby declare the following to be a full, clear, and exact description of the invention, such as will enable others skilled in the art to which it appertains to make and use the same.

This invention has for its object the simplification of the working of telephone-stations; and it consists in carrying out by automatic 15 apparatus several of the operations that have hitherto been effected by hand and which are repeated in making each connection, such automatic apparatus being brought into action on effecting a certain manipulation and being 20 then made to effect a number of subsequent operations in the required order.

I will describe the said invention with reference to the accompanying diagrammatic drawings, in which—

25 Figure 1 is a diagrammatic view of a telephone system embodying my invention. Fig. 2 is a similar view of the automatic apparatus for facilitating the operation of the system. Fig. 3 is a perspective view of the automatic switch.

Referring more particularly to the drawings and letters and figures of reference thereon, Fig. 1 shows at the left hand two subscribers' lines $T' T^2$, running through three switchboards of a station, and at the right hand a glow-lamp board $G T$, the several lamps $g g$ of which serve to give a visible indication of the fact whether the corresponding line is free or engaged. This is effected in such manner that the circuit of a glow-lamp is closed both by the falling of the indicator-shutter as also by the plugging of a jack of the same number, so that the glow-lamp is lighted up as long as the said line is engaged.

45 Fig. 2 shows at the right hand the speaking instrument of the operator (microphone M , telephone T , induction-coil, and microphone-battery) and the call-bell battery $W B$, the continuous current of which is changed to 50 an alternate current by means of the pole-changer $P W$ if the subscribers have polarized call-bells. To the left hand are two plugs

S' and S^2 of an ordinary double-cord connection, set with an intermediate ring-off drop $S K$, and in the middle is the before-mentioned automatic switch device, which will be presently explained.

When a subscriber—for instance, T' —calls, his indicator-shutter K' falls at the switchboard I of the station and bears against the contact-wire d . A current then passes from the glow-lamp battery B through the switchlever H , which ordinarily is situated on the contact 2 of the switch apparatus U , and through the glow-lamp board $G T$, lamp g' , 65 contact-wire d , shutter K' , and back to the battery. As soon as the shutter K' falls the operator at switchboard I raises the rear plug S' of one of his double cords and inserts it into the jack k' of his board. The two springs f^1 and f^2 of the jack k' are thus connected together by means of the insulated ring r of the plug, and as f^1 is connected with the glow-lamp and f^2 with the battery B a second circuit for the current passing through the glow-lamp is thus formed. The latter therefore continues to glow if the operator 70 now raises the fallen shutter K' again. The speaking instrument of the operator is now connected, as seen on the drawings, with the double-wire line of the subscriber T' through $c^2 H^4 i'$, end s of the plug S' , and through $c^4 H^3 i^2 k$ and jack k' as the body k of S' makes contact with the socket h of k' , and the end s bears against the spring f^3 , so 75 as to separate it from f^4 , so that K' is cut out of circuit. The operator then announces, “Here, exchange,” whereupon the subscriber gives the number of the required subscriber, such as No. 2. The operator then looks past 80 his switchboard to the glow-lamp board, situated some feet away, in order to ascertain whether the line T^2 is free or not. He then answers “free” or “engaged,” as the case may be. If it is free, he raises his front plug S^2 and inserts it into the jack k^2 of the subscriber No. 2, whereby the glow-lamp g^2 is lit up, as before described. On the raising of S^2 the levers $H^1 H^2$, pivoted upon the axis a' , and with them the levers $H^3 H^4$, mounted on H^2 , 85 but insulated therefrom and from each other by insulation 1 , turn under the influence of the springs $i^1 i^2$ in the direction of a clock-hand until the pin Z bears against the disk

s'. This latter is fixed to the disk *s*², and both are mounted frictionally upon the axis *a*², which is continuously rotated by a motor, (indicated by a belt *a*³.) As soon as *Z* moves downward the abutment *o* will be free, and the two disks in following the motion of the axis *a* can rotate in the direction of the arrow. As long as *Z* bears against *s'* neither of the springs *i*³ and *i*⁴ touch their contacts *c*' and *c*³. The parts *s* and *h* of plug *S*² will be connected with call-battery *W B* while disk *s*² is rotating, except when notch *s*³ in the periphery of said disk allows the insulating projection *s*⁴ to drop toward axis *a*, allowing springs *h*' *h*² to draw springs *h*⁵ *h*⁶ away from contacts *c*⁵ *c*⁶, breaking connection to the call-battery. During the rest of rotation of disk *s*² springs *h*' *h*² will be pressed to the right, allowing opening springs *h*⁵ *h*⁶ to rest against contacts *c*⁵ *c*⁶, connected to the call-battery, whereby the call-battery will be connected into any line in whose spring-jack plug *S*² is inserted.

*s*⁶ is a metal piece which electrically connects springs *h*' and *h*².

Shortly after the insulating-piece on *h*² again engages with the notch *s*³ of the disk *s*² the pin *Z* falls into the notch *e* of disk *s'*, and thus stops disks *s'* and *s*², which, as before stated, are held frictionally, for example, by a friction-disk *s*⁵, bearing against disk *s'*. In addition this motion of *Z*—that is, of *II*² *II*³ *II*⁴—causes the corresponding contact-springs *i*³ and *i*⁴ to bear against their contact *C'* and *C*³, whereby the two plugs are connected directly with each other through the ring-off drop *S K*, thus completing the connection. When the conversation is finished, the two subscribers ring off, when the shutter *S K* will fall. The operator then draws the plugs opposite the ring-off drop out of the jacks, whereby the glow-lamps *g*' and *g*² are extinguished. The front plug *S*² falls on the lever *II'* and turns it, and also the levers *II*² *II*³ *II*⁴, back into the position shown in Fig. 2, so that the disks *s'* and *s*² can turn a small distance farther until the abutment *o* bears against the pin *Z*, whereby they are stopped again.

For nightworking a call-bell *W* is provided, which, as shown, is put in circuit on bringing lever *II* upon the contact *3*.

Having now particularly described and ascertained the nature of this invention and in what manner the same is to be performed, I declare that what I claim is—

1. The combination of telephone-lines, spring-jacks to which the lines are connected,

switch-plugs, connecting-wires therefor, a switch operated in one direction by a spring and in the opposite direction by the weight of one of said plugs, an operator's telephone normally connected between said plugs by said switch and disconnected when the switch is operated on the lifting of the plug, an automatic switch adapted to connect a signal-generator between the plugs, and a detent for said automatic switch directly controlled by the weight of the plug which controls said first-mentioned switch.

2. In a telephone system the combination with the subscriber's lines and their respective jacks and plugs, of an automatic switch or contact-making apparatus comprising a continuously-rotating shaft, a disk or disks held frictionally thereon and having a cam-surface and stops, and means for holding said disk from rotation comprising the levers *II'* *II*², contacts carried by said levers, and contacts actuated by said cam-surface.

3. The combination of plugs *S'* *S*², connecting-wires therefor, an automatic switch between said plugs comprising a driving-shaft with a cam-disk frictionally mounted thereon, a pivoted stop-lever *II*² normally held in position to stop the cam-disk by the weight of one of the plugs acting thereon, contacts *II*³ *II*⁴ normally in connection with plugs *S'* *S*² and also with the operator's telephone, contacts *II*³ *II*⁴ being connected to lever *II*² so as to move therewith, thereby breaking connection with the operator's telephone, and switch-contacts controlled by the cam-disks for connecting and disconnecting a signal-generator to and from the plugs, as described.

4. An automatic switch apparatus for telephone-exchanges consisting of the combination with the plug or connection-cords, the operator's telephone and the call-battery, of a number of contacts inserted in the said connecting-cords, a shaft continuously rotated by a suitable motor, disks loosely mounted on said shaft and having suitable cam-surfaces, means for coupling said disks with said shaft automatically by the action of lifting up the connection-plug, and means for operating said contacts by the rotation of the said disks, substantially as and for the purpose set forth.

In testimony whereof I have affixed my signature in presence of two witnesses.

JULIUS HENRIK WEST.
